UNITED STATES PATENT OFFICE.

CLIFFORD S. GOBY, OF CLEVELAND, OHIO, ASSIGNOR TO THE ENGINE HOLDINGS COMPANY, OF CLEVELAND, OHIO, A CORPORATION OF OHIO.

INTERNAL-COMBUSTION ENGINE.

1,133,852.

Specification of Letters Patent. Patented Mar. 30, 1915.

Application filed July 17, 1912. Serial No. 709,927.

To all whom it may concern:

Be it known that I, CLIFFORD S. GOBY, a citizen of the United States, residing at Cleveland, in the county of Cuyahoga and State of Ohio, have invented a certain new and useful Improvement in Internal-Combustion Engines, of which the following is a full, clear, and exact description, reference being had to the accompanying drawings.

This invention relates to internal combustion engines of the type shown in my applications No. 514,098 filed August 23, 1909 and No. 568,612 filed June 24th, 1910. In the construction disclosed in these two applications, each cylinder is provided with a pair of valves, namely—an inlet valve and an exhaust valve, the valves being of the slideable sleeve type located at one side of and substantially parallel with the cylinder and sliding between a cylindrical surrounding casing and an internal liner sleeve, the outer seat or casing and the liner sleeve forming an annular slide-way for the valve. In the form of my invention shown in the later application above-mentioned, the upper end of the sleeve is exposed, whereby it is possible for a slight pumping action to occur upon the inlet and exhaust pipes (according as the valve is an inlet or an exhaust valve) although such action is necessarily small, owing to the limited cross-sectional area of the upper or exposed end of the valve sleeve. In both forms of my invention disclosed in the aforesaid applications, an abutment is anchored within each valve (being preferably formed with the liner) at one side of the registering ports of the liner and the valve seat, whereby the gaseous mixture entering the inlet valve and the exploded gases entering the exhaust valve will be deflected and the gases will be prevented from entering the crank case or the case which contains the lay shaft by which the valves are driven.

In the embodiment of my invention disclosed herein, I entirely eliminate the slight pumping action referred to by connecting the abutment (which may be conveniently carried by and movable with the liner sleeve) with the lay shaft and so connecting the abutment and the valve that their phases will be practically in opposition to each other; that is to say, when the valve is ascending, the abutment is descending, and

vice versa. Furthermore, owing to the far greater cross sectional area of the abutment than that of the valve, I give to the liner and its abutment a length of stroke which is inversely proportional to the cross sectional areas of the reciprocating parts. The result is to entirely balance or off-set the slight pumping action due to the exposed cross sectional area of the ring or annulus of the valve.

In the drawing forming part hereof, Figure 1 represents a view, partly in side elevation and partly in vertical section, of an engine constructed in accordance with my invention, and Fig. 2 a sectional view taken through one of the valves, at right angles to the plane of section in Fig. 1.

Describing by reference characters the various parts illustrated herein, 1 denotes the base section or crank case of an engine, the engine being shown as of the four-cycle type comprising generally the cylinder 2 having a casing 3 surrounding and forming a water jacket therewith, the liquid within the water jacket and parts being indicated generally at 4. Each cylinder is provided with a cover section 5 and with a spark plug 6, which may be carried by a bushing 7 threaded into the top of the cylinder.

Cast with each cylinder 2, but preferably spaced therefrom a short distance, is a valve casing, said casing being preferably a cylindrical sleeve 7 having about midway of its length a series of segmental ports 8, the series extending substantially entirely around the sleeve and communicating with a duct 9 carried by and merging with the head of the cylinder 2. This sleeve depends from the cover section 5, being preferably cast with the cylinder head and with the wall of the duct 9, and is provided at its lower end with a ring 10 threaded thereon and abutting against an inwardly directed flange 11 carried by the casing 3, the flange extending entirely around the sleeve and forming the top of the chamber which contains the lay shaft. A packing ring 12 is inserted between the top of the ring 10 and the flange 11.

Within the sleeve 7 is mounted the tubular slide valve 13, said valve being cylindrical in shape and being connected at its lower end by a pitman 14 with the crank 15, which projects from the lay shaft 16. The valve

13 is provided about midway of its length with a series of segmental ports 17 adapted to communicate with the corresponding ports 8 in the outer sleeve or valve casing 7. Within the slide valve 13 there is mounted a liner or bushing 18, said liner or bushing having a transverse partition or abutment 19 extending thereacross immediately below a series of segmental ports 20 which correspond to and are adapted to register with the ports 8 and 17. The liner 18 and the valve casing 7 provide an annular valve seat for the cylindrical slide valve and, in order to prevent leakage between the sleeve 7 and the liner 18, the valve is provided with packing rings 21 and the liner with packing rings 22, the packing rings in each case being located above and below the segmental ports of their respective supporting members. The cover section 5 is provided with suitable openings in its top above the inlet and exhaust valves, an opening for one of such valves being shown in the drawings and being covered by the plate 23, which 25 may be conveniently and removably anchored by means of the bolt 24 having a cross head 25 at its lower end adapted to extend across the bore of the valve chamber beneath the cover and to engage the flange 30. The cover is secured in place by means of a nut 27 on the upper end of the bolt. The valve shown in the drawing is an outlet valve, in which case the top of the valve will communicate by means of a branch 28 35 with an outlet pipe 29 which may be common to all of the outlet valves used with the multi-cylinder engine. In such case, the inlet valve, which is identical in construction with the outlet valve, will be supplied by 40 means of an inlet pipe 30 which may be a branch from a common supply pipe for all of the inlet valves of the multi-cylinder engine, as shown in my application No. 568,612.

45 With the construction shown, there will be a slight pumping effect on the pipe 28 due to the area of the exposed end of the valve 13. To off-set this slight pumping action, the liner sleeve 18 and its abutment 50 is connected to the shaft 16 by means of a connecting rod or pitman 31. The connecting rods or pitman 31 and 14 will be connected with the lay shaft 16 at an angle of substantially 180 degrees apart, and the 55 strokes of the connecting rod 31 and 14 will be inversely proportional to the cross sectional area of the upper exposed surfaces of the moving parts connected therewith. Furthermore, the parts will be so arranged 60 that, when the ports 17 are in register with the ports 8, the ports 20 will also be in register with the ports 17.

As in the disclosure of my prior invention, the rear or outer parts of the duct 9, which 65 is formed with the valve seat 7, will be later-

ally deflected to form a channel 32 surrounding the portion of each valve sleeve which is remote from the cylinder head, thus producing a balanced construction which minimizes the tendency of the valve sleeve to bind and causes it to wear evenly in its seat. The partitions or abutments 19 not only serve to direct the incoming and outgoing gases, but isolate the crank case and lay-shaft chamber from such gases. 75

Having thus described my invention, what I claim is:

1. In an internal combustion engine, the combination of a cylinder, a valve casing having a port communicating with said cylinder, a tubular valve reciprocably mounted within said casing and controlling said port, a fluid duct communicating with said casing and arranged to supply fluid fuel to said port, one end of said valve being exposed to such fluid, a slidable member located within the valve and arranged to deflect the fluid through the valve casing port, and means for reciprocating said valve and member in opposite directions. 80

2. In an internal combustion engine, the combination of a cylinder, a valve casing having a port communicating with said cylinder, a tubular valve reciprocably mounted within the casing and having a port adapted to communicate with the former port, a fluid duct communicating with the interior of the valve and exposed to the action of one end of the valve, an abutment within said valve adapted to deflect fluid passing through the port in said valve, and connections for operating the valve and the abutment in opposite directions through distances inversely proportional to the cross sectional areas thereof. 90

3. In an internal combustion engine, the combination of a cylinder, a valve casing having a port communicating with said cylinder, a tubular valve reciprocably mounted within the casing and having a port adapted to communicate with the former port, a tubular liner slidably mounted within said valve and having ports intermediate of its ends adapted to register with said valve ports, a fluid duct communicating with the interior of said liner, an abutment within said liner on the side of the port thereof opposite to the fluid duct, and means for reciprocating said valve and liner in opposite directions so as alternately to align and dis-align said ports. 105

4. In an internal combustion engine, the combination of a cylinder, a valve casing having a port adapted to communicate with said cylinder, a tubular valve reciprocably mounted within said casing and having a port adapted to communicate with the former port, a liner within the valve having a port adapted to communicate with the former ports and having an abutment at 110

- one side of the port therein, and connections for operating said sleeve and liner in reverse directions each a distance inversely proportional to the cross sectional area of the exposed part thereof. 30
5. In an internal combustion engine, the combination of a cylinder, a crank case, a valve casing separate from the cylinder and at one side thereof and having a port communicating therewith and having its bottom in open relation to the crank case, a tubular valve reciprocably mounted within said casing and having a port adapted to communicate with the former port, a liner within 35
- 10 said valve having a port adapted to communicate with the former ports, an abutment at one side of the liner port, and connections for reciprocating said valve and liner in reverse directions.
- 15 6. In an internal combustion engine, the combination of a cylinder, a crank case, a valve casing separate from the cylinder and having a port communicating therewith and having its bottom in open relation to the 40
- 20 crank case, a tubular valve reciprocably mounted within said casing and having a port adapted to communicate with the former port, a liner within said valve having a port adapted to communicate with the former ports, an abutment at one side of the liner port, and connections for reciprocating said valve and liner in reverse directions. 45
- 25 7. In an internal combustion engine, the combination of a cylinder, a valve casing having a port communicating with said cylinder, a tubular valve reciprocably mounted within the casing and having a port adapted to communicate with the former port, an abutment within said valve and located at one side of the first mentioned port, a fluid duct communicating with the valve casing and arranged to subject one end of said 50
- 30 valve to the pressure of such fluid, and connections for operating the valve and the abutment in reverse directions each a distance inversely proportional to the cross sectional area of the part thereof which is exposed to the pressure of such fluid. 55
- In testimony whereof, I hereunto affix my signature in the presence of two witnesses.
